UNITED STATES PATENT OFFICE.

JOSEPH STONE, OF BATAVIA, ILLINOIS, ASSIGNOR TO BENJAMIN DANFORTH,
OF SAME PLACE.

IMPROVEMENT IN MACHINES FOR MAKING HORSESHOE-NAILS.

Specification forming part of Letters Patent No. 124,771, dated March 19, 1872.

SPECIFICATION.

I, JOSEPH STONE, of Batavia, in the county of Kane and State of Illinois, have invented a new and useful Improvement in Horse-Nail Machines, of which the following is a specification, reference being had to the accompanying drawing.

The Nature and Object of my Invention.

My invention relates to that class of horse-nail machines shown and described in the American Letters Patent No. 25,183, No. 25,309, and No. 41,141, issued to Daniel Dodge, and to which reference is made for a description of that part of the machine which holds the nail-rod, forges the nail on the end of the rod, and then thrusts it forward to the cutters, which cut the point of the nail and sever the nail from the rod in a finished state. My invention is an improvement on the above-named machine; and it consists in the combination of the hook Q and the cutter S, arranged and operating to draw the point of the nail to the center, and to cut off any sharp point that may be left on the nail by the cutters D and G, as hereafter described, thereby giving the nail-point a more complete finish than has heretofore been done; and my invention further consists in the combination and arrangements of the several parts, hereinafter fully described, that operate the hook Q simultaneously with the cutters E and D, noiselessly and with a very little friction.

Description of the Drawing.

Figure 1 represents a side elevation of that part of a horse-nail machine to which my invention relates; Fig. 2, a top or plan view of the same; Fig. 3, an end view; and Figs. 4, 5, and 6, a side view of the nail in its different stages of being pointed.

General Description.

A is the base frame of the machine; B, the rock-shaft, driven in the ordinary way; and C, the arm that carries the vibrating cutters D and E. F is the ordinary anvil or block, to which is attached the stationary or fixed cutter G. These parts are the same as shown in machines now in use; and the nail-rod, represented by the dotted lines H, is held and fed to the cutters obliquely, the same as in other

machines in use. I is a vibrating arm or lever, pivoted at J, and having one end attached to the arm C, by which it is vibrated, and the other so connected to the bar K as to give it a horizontal motion, as hereafter described, when the lever is vibrated. The bar K is suspended on the hangers P, which swing from the cross-piece V, as indicated by the dotted lines. The cross-piece V is rigidly attached to the post or upright U. R is a spring, resting against the end of the bar K to throw it forward. Q is the hook that hooks over the point of the nail after it is thrust forward from the forging part of the machine and before it is severed from the nail-rod. The nail, in being forged, is drawn out sufficiently to extend more or less past the hook Q when it is thrust forward. The hook begins to pull against the point of the nail as the cutters D and G begin to shear the metal from the side of the point, and the point of the nail is gradually bent by the pulling of the hook, so that, just as the said cutters are done cutting, thereby forming a more complete point to the nail than is formed by forging, the hook has bent the point to the center of the nail. These cutters, in making the shearing-cut of the metal from the side of the point of the nail, leave a fine wiry point at the lower side of the point of the nail, which may still be attached to the metal cut from the nail in forming the point. The cutter S is so placed that the hook, just as the cutters D and G finish cutting and the point of the nail is bent to its center, presses this fine wiry point against it, and by cutting it off makes a more finished point to the nail. The hook Q is attached to the bar K by a setscrew, so that it can be adjusted as desired. S is an adjustable cutter, attached to the block F, so that the hook Q causes the point of the nail, when it is drawn to the center, to strike it and cut off the sharp point of the nail at the place indicated by the line at the point of Fig. 6.

When the arm C is thrown down and carries the cutters to the nail to cut the point, it also vibrates the lever I and throws back the bar K, which draws the hook Q against the point of the blank, as it is being cut, and draws it to the center of the blank, where it strikes the cutter S and the sharp point is cut off. The spring R throws the bar K with the hook Q forward again ready for another operation, as above described. The cutter E severs the nail

from the nail-rod the same as in the Dodge machines, but not till after the other cutters have finished the point, so that when the nail is severed from the rod it falls from the machine finished.

I manufacture a center-pointed horse-nail with the feather point removed ready for use.

Claims.

What I claim, and desire to secure by Letters Patent, is—

1. I claim the cutter S, in combination with the hook Q, when constructed and operating substantially as and for the purpose specified.

2. I claim the lever I, bar K, hook Q, and arm C, when arranged and operating substantially as and for the purposes set forth.

JOSEPH STONE.
